UNITED STATES PATENT OFFICE.

WILLIAM A. TRAVER, OF PROVIDENCE, RHODE ISLAND, ASSIGNOR TO FRANKLIN PROCESS COMPANY, OF PROVIDENCE, RHODE ISLAND, A CORPORATION OF RHODE ISLAND.

HEATER FOR WATER OR OTHER FLUIDS.

1,200,545.

Specification of Letters Patent.

Patented Oct. 10, 1916.

Application filed February 2, 1916. Serial No. 75,749.

To all whom it may concern:

Be it known that I, WILLIAM A. TRAVER, a citizen of the United States, residing at Providence, in the county of Providence, 5 State of Rhode Island, have invented certain new and useful Improvements in Heaters for Water or other Fluids, of which the following is a specification.

My invention is an improved heater for 10 use with dyeing-keirs, kettles, vats or similar apparatus employed in various arts.

My improved heater is intended for use 15 particularly in heating dye-liquor, mordanting-fluid or washing-water during the process of dyeing, bleaching, scouring, washing or otherwise treating textile materials with a fluid bath.

The object of my invention is to simplify 20 the construction and improve the arrangement of the apparatus to increase its efficiency, and particularly to provide for easier access to its interior and a more convenient method of removing and reassembling its 25 parts for the purpose of cleaning, repair or replacement.

The method and means for carrying out 30 these improvements are fully described in the following specification, illustrated by the accompanying drawings, in which like reference characters designate like parts.

In the drawings:—Figure 1 is a sectional elevation of my improved heater; and Fig. 35 2, a plan view of the same showing its exterior shell in section to illustrate the parts inclosed therein.

Referring first to Fig. 1, my improved heater is preferably constructed in the form 40 of a cylindrical tank or container A comprising the convex end heads B and C and the outer inclosing drum or shell S. The head B forms the base of the tank and is provided with a flanged rim b to which is bolted the rim d of a transverse, circular plate or diaphragm D. At the center of a 45 convex base B is an opening b' surrounded by an interiorly-threaded flange or collar F held in place by the bolts f. Screwed into the flange F is a pipe E which is adapted to be connected with the boiler or other source 50 of the steam which acts as the heating agent and is admitted into the bottom of the heater beneath the diaphragm D. Screwed into the diaphragm D and extending vertically upward therefrom are a plurality of relatively

small pipes d', d', through which the steam 55 passes to communicate its heat to the fluid in the main compartment of the tank A. As many steam-pipes d' are provided as can be conveniently inclosed within the shell S in spaced apart relation, being either arranged in concentric circles or in the form of a geometric figure as shown in the plan view, Fig. 2.

Overlying the top of the diaphragm D and spaced a slight distance above it is a 60 circular plate G which forms a false-bottom for the tank A. The false-bottom G is constructed in the form of an inverted cup having a depressed, annular rim or flange g which rests on the rim d of the diaphragm 65 D overlying the flanged rim b of the base B. Overlying the flange g is a circular collar or ring H having its rim h formed with an up-standing web or flange h' to the inside of which is riveted the outer, cylindrical shell 70 S. The shell S also has a flanged ring J surrounding its top and riveted thereto to provide a means for attaching the head or cover C to the tank. Preferably the cover 75 C is of the same form as the base B and is secured in place by means of the bolts c reaching through holes in its flange and in the ring J. A pipe K is screwed into a collar k which is bolted to the top of the cover 80 C surrounding its central opening c', and serves as the outlet for the tank to provide 85 for the egress of the heated water or other fluid therefrom. The pipe K leads to the keir or other apparatus in which the heated liquid is employed during the dyeing or 90 other process. The ingress for the fluid into the tank is preferably near its base and, as shown in Fig. 1, consists of a pipe L screwed 95 into a collar l which is riveted to the side of the shell S.

Inclosing the steam-pipes d' are a plurality of larger pipes P, screwed into the false-bottom G. The pipes P extend upwardly some distance above the tops of the steam-pipes d' and are closed at their ends 100 by the caps p. It will be noted that a space is left between the outside of the steam-pipes d' and the interior of the pipes P to allow the steam to circulate therein. At their lower ends the pipes P open into the 105 space between the diaphragm D and the false-bottom G and to take care of the condensation of the steam in this compartment.

of the tank a drip-pipe O leads therefrom down through the base B. The drip O is usually connected to a suitable drain leading to a catch-basin or sewer.

5 The particular and novel features of my invention which provide for the improvements hereinbefore referred to are first: the arrangement of the means for bolting the several parts of the base of the heater together to provide for removing the outer shell without disturbing the relation of the diaphragm D and false-bottom G; and secondly, the arrangement of the standpipes of the heater whereby any one of them may be 10 taken out by itself without necessitating the removal of the adjacent pipes. Referring to Figs. 1 and 2, it will be noted that the base B, diaphragm D, false-bottom G and ring H are all held together by the bolts N inserted 15 from the bottom through suitable holes in their rims b, d, g, h. Applied to the upper ends of the bolts N are nuts n which are screwed down against the rim h of the ring H to bind the several parts together, and 20 usually packing-rings or gaskets, not here shown, are placed between the joints to render them fluid-tight.

Besides the bolts N I also provide four bolts M, shown by dotted lines in Fig. 2, and 30 at the right in Fig. 1, which reach up through alining holes in the flange b of the base B and rim d of the diaphragm D with their ends screwed into the rim g of the false-bottom G. This provides that when 35 the main holding bolts N are removed to allow for lifting off the shell S, the auxiliary bolts M will still hold the base B, diaphragm D and false-bottom G together without disturbing their relation. That is to say, the 40 shell S and its holding-ring H may be removed from the base of the tank by simply unscrewing the nuts n without disturbing the arrangement of the other parts of the base or loosening their joints. Heretofore, 45 in all apparatus of this type, it has been necessary to disconnect the lower head or base, the diaphragm and the false-bottom in removing the outer shell of the tank and then to reconnect all the parts when the shell 50 is again replaced. In other words, the several joints must be disconnected and their gaskets disturbed so that refitting and re-packing of the joints is necessary when the parts are assembled again.

55 It frequently happens with heaters employed for the purposes herein enumerated that the pipes become rusted, corroded or clogged and require cleaning or replacement. When this becomes necessary it is an easy 60 matter with my improved arrangement to simply unfasten and lift off the shell S with its attached cover C without disturbing or disarranging the other parts of its base. In addition to the present improved arrangement for removing the shell S I have also

provided a much simpler and more convenient method of individually disconnecting the standpipes of the heater. Referring to Fig. 1, it will be noted that the pipes P of the cluster or series in the shell S are of 70 graduated lengths. Referring also to Fig. 2, the outer ring or set of pipes P' are the shortest, with the next inner set P² slightly longer, the next set P³ still longer, and finally the center pipe P⁴ longest of all. 75 This provides that the several sets of pipes will project one a slight distance above another toward the center of the cluster. The purpose of this arrangement which constitutes an important feature of the invention 80 is to provide for reaching across the tops of the outer pipes with a wrench so as to allow for attaching it to any one of the inner pipes in the series. That is to say, if it is required to remove the central pipe P⁴, 85 for instance, for cleaning or replacement a wrench W, shown in dotted lines in Fig. 1, can be applied to its upper projecting end without interference with the other pipes arranged around it. Likewise, any one of 90 the series of pipes P³ may be grasped with a wrench above the pipes P² and pipe P' so that they can be turned in either direction, without interference, to unscrew them from the false-bottom G or to replace them in 95 their sockets. It will be noted by reference to Fig. 1 that the small, inner steam-pipes d' are also graduated in length proportionately to the inclosing pipes P so that their removal and replacement are accomplished 100 in the same manner as above described. Through this arrangement any one pipe or set of pipes may be removed and replaced without displacing the several adjacent pipes surrounding it, whereas, in all heating-tanks 105 as heretofore employed it has been necessary to start at the outside and remove all of the adjacent pipes before one or more of the central pipes could be reached with a wrench. This work entails considerable extra labor 110 and consumes valuable time, whereas, with my present improvement, any individual pipe in the group may be selected and removed without disturbing its neighboring pipes. In this way a considerable saving 115 of time and labor is effected during the cleaning or repairing of the heater and furthermore the whole arrangement is much easier to assemble during its manufacture.

In use my improved heater operates in a well-known manner as follows: Steam is admitted through the intake-pipe E and distributed through the diaphragm D to the several small standpipes d'. From the upper, 120 open ends of the pipes d' it circulates down through the radiating pipes P and into the space between the false-bottom G and diaphragm D, from which the condensation is carried off through the drip O, or, if preferred, 125 a return pipe may be led back to the boiler. 130

The water or other fluid to be heated enters through the ingress-pipe L and, as generally provided, is forced through the heater and its connected keir or other apparatus by 5 means of a circulating pump. As the fluid circulates between the standpipes P the heat generated by the steam is radiated therefrom and, as the fluid becomes heated, a thermosiphon action is set up with the hottest fluid 10 rising to the top of the tank A. In some cases this action is sufficient to maintain a constant circulation of the fluid through the tank, drawing it in from the intake L and forcing it out through the pipe K with 15 the hottest portion always feeding first.

Usually a water-gage is provided on the top of the tank and a thermometer is employed to indicate the temperature of the heated fluid so that the supply of steam may 20 be regulated as required. These devices, however, form no part of the present invention and therefore are not herein shown or described.

It will be understood that I do not herein 25 claim broadly the general arrangement of the type of heater shown and described, but only the particular features of construction which make for the advantages above pointed out.

30 What I claim is:—

1. In a heater for water or other fluids, the combination with a closed tank having 35 an inlet and outlet for the fluid to be heated and an intake for the steam, of a series of pipes grouped around the interior of the tank and communicating with the steam intake, said pipes being of graduated lengths arranged with the longest one in the center 40 of the group and with the others stepped down in shorter lengths toward the outer walls of the tank.

2. In a heater for water or other fluids, the combination with a closed tank having 45 an inlet and outlet for the fluid to be heated and an intake for the steam at one end of the tank, of a diaphragm extending across the tank adjacent the steam intake, and a group of steam-pipes of graduated lengths secured in openings in the diaphragm and 50 arranged with the longest pipe in the center and with the others stepped down in shorter lengths toward the outer walls of the tank.

3. In a heater for water or other fluids, the combination with a closed tank having 55 an inlet and outlet for the fluid to be heated and a steam intake at one end of the tank, of a plurality of steam-pipes grouped in spaced relation around the interior of the tank and communicating with the steam intake, and a series of larger pipes inclosing the steam-pipes with a space between their walls for the circulation of the steam there-through, said steam-pipes and their inclos- 60 ing pipes being of graduated lengths with the shortest pipes on the outside of the

group and the inner ones projecting beyond the ends thereof in stepped relation toward the center of the group.

4. In a heater for water or other fluids, the combination with a closed tank comprising 70 a cylindrical shell having end heads connected thereto with an inlet and outlet for the fluid to be heated, of a diaphragm extending across the tank at its base, a false-bottom overlying the diaphragm in spaced relation thereabove, a steam intake communicating with the compartment below the diaphragm, a series of vertical steam-pipes extending through the false-bottom and secured in openings in the diaphragm in communication with the steam compartment, and a plurality of larger standpipes secured 75 in openings in the false-bottom inclosing the steam-pipes with their upper ends closed above the open ends of the steam-pipes, said 80 steam-pipes and standpipes being of graduated lengths grouped in series with the shortest pipes on the outside of the group and the inner pipes gradually stepped upwardly toward the center to provide for 85 grasping the pipes individually with a wrench one above the others.

5. An improved heater for water or other fluids comprising a tank having a convex base formed with a flanged rim, a diaphragm 95 arranged with its rim overlying the flange of the base, a false-bottom having a depressed rim overlying the rim of the diaphragm, a flanged ring overlying the rim of the false-bottom, a cylindrical shell 100 riveted to the flange of the ring, a cover secured to the opposite end of the shell, a plurality of bolts reaching through the several overlying rims of the base, diaphragm, false-bottom and ring to draw the parts together to seal their joints, and a series of 105 shorter bolts extending through the rims of the base and diaphragm and screwed into the rim of the false-bottom to hold these parts together while allowing the removal of the shell and its holding ring.

6. An improved heater for water or other fluids comprising a tank having a convex base formed with a flanged rim and provided with a steam intake, a diaphragm arranged with its rim overlying the rim of the base, a series of vertical steam-pipes secured in openings in the diaphragm, a false-bottom spaced above the diaphragm and formed with a depressed rim overlying the rim of the diaphragm, a plurality of standpipes secured in openings in the false-bottom with their walls inclosing the steam-pipes, a ring overlying the rim of the false-bottom and provided with an upstanding flange, a cylindrical shell riveted to the flange of the ring, a similar ring riveted to the top of the shell, a cover secured to said last named ring, a plurality of bolts extending through the rims of the base, dia- 120 125 130

phragm, false-bottom and lower ring to secure the parts together with fluid-tight joints, and a series of auxiliary bolts extending through the rims of the base and diaphragm and screwed into the rim of the false-bottom to hold these parts together when the shell is removed by removing the main bolts extending through its holding ring.

- 10 7. An improved heater for water or other fluids comprising a tank having a convex base formed with a flanged rim and provided with an intake for the steam, a circular diaphragm arranged with its rim 15 overlying the rim of the base, a series of vertical steam-pipes screwed into openings in the diaphragm, a false-bottom spaced above the diaphragm and formed with a depressed flange overlying its rim, a plurality 20 of standpipes screwed into openings in the false-bottom to inclose the steam-pipes extending therethrough and grouped in series

with the shortest pipes on the outside and increasing in length toward the center of the group, a ring seated against the rim of the false bottom, a cylindrical shell fastened to the ring and extending upwardly therefrom to inclose the group of standpipes, a cover secured to the top of the shell, a series of bolts extending through the rims of the base, diaphragm, false-bottom and shell-ring to draw the parts together, and a series of shorter bolts reaching through the base, diaphragm and false-bottom to hold these parts together when the shell is removed by releasing the main bolts extending through its ring.

In testimony whereof I affix my signature in presence of two witnesses.

WILLIAM A. TRAVER.
